UNITED STATES PATENT OFFICE.

HENRY S. FURMINGER, OF MITTINEAGUE, MASSACHUSETTS, ASSIGNOR OF ONE-HALF TO WILLIAM H. MILLER, OF SPRINGFIELD, MASSACHUSETTS.

MAGNETIC SHUTTLE-MOTION FOR LOOMS.

SPECIFICATION forming part of Letters Patent No. 773,010, dated October 25, 1904.

Application filed July 15, 1902. Serial No. 115,713. (No model.)

To all whom it may concern:

Be it known that I, HENRY STREET FURMINGER, a citizen of the United States of America, residing at Mittineague, in the county of Hampden and State of Massachusetts, have invented new and useful Improvements in Looms, of which the following is a specification.

This invention relates to improvements in looms; and it has especial reference to the construction of the shuttle-operating mechanism whereby the picker-sticks may be done away with; and the object of the invention is to provide improved means for propelling a shuttle transversely of the warp-threads by electrically - operated means, the invention consisting in improved devices carried on the lay-beam whereby an electromagnet may be reciprocally operated transversely of and beneath the warp-threads and in means for operating a shipper mechanism at the end of said transverse movement of the magnet in either direction, whereby the movement of the latter may be reversed.

In the drawings forming part of this application, Figure 1 is a sectional elevation of a loom having my invention applied thereto. Fig. 2 is an enlarged plan view of the carrier by means of which the magnet may be reciprocally operated. Fig. 3 is a perspective view of a part of the lay-beam and the devices carried thereon for moving the shuttle, all on a somewhat enlarged scale. Fig. 4 is a perspective view of a piece of woven fabric and of a movable finger, around the end of which a weft-thread is drawn temporarily during the movement of the shuttle.

In the drawings forming part of this application no particular form or type of loom has been shown, and the various elements of the machine, except such as relate to the invention, may be considered as purely conventional.

In the drawings, *a* indicates the frame of a loom; *b*, the heddles; *c*, a cam-shaft driven by a suitable belt, there being cams on said shaft, (which will be described farther on,) whereby the lay-beam *d* may be given the

proper reciprocatory movements to beat up the fabric. On another cam-shaft, *e*, there is a cam *f*, whereby the levers *g*, connected to the heddles *b*, may be operated to impart to said heddles proper alternate reciprocatory movements in a vertical plane to effect the separation of the warp - thread. Mounted upon the lay-beam *d* is the reed-frame *h*.

The lay-beam *d* slides in a horizontal plane on two tracks *i*, secured to the frame *a*, as shown in Figs. 1 and 3, there being suitable shoes *j* bolted to the ends of the beam, which fit over said tracks and support the beam. This beam is given reciprocatory horizontal movements on said tracks by means of a connecting-arm *k*, pivotally connected to said beam and to the end of an arm *m*, pivotally supported at *n*, and whose opposite end engages the heart-shaped cam *o*, whereby a suitable beating-up movement is imparted to the lay-beam. On the front of the lay-beam there are two tracks *p*, parallel with said beam, on which a sliding carriage *q* is mounted, which carriage carries the electromagnet *r*, which is housed under an inclined plate *s*, whose face is parallel substantially with the lower line of warps, the surface of the plate lying in close proximity to said warp.

Depending from the under side of the carriage *q* is a hanger *t*, which supports a rock-shaft *u*, each end of which is bent at right angles to the shaft in opposite directions in substantially the same plane, constituting arms whereby the shaft *u* may be rocked; and on this shaft there is secured in any proper way a down-hanging arm *v*, whose lower extremity is provided on two opposite sides thereof with the vertical ribs *w*.

Beneath the lay-beam and carried thereby in suitable bearings are two vertical shafts *y*, (shown in Fig. 2,) carrying sprocket-wheels *z*, over which runs the belt *3*, whose inner surface is provided with vertical ribs *4*, which engage with the teeth of the wheels *z*, one of which is driven by the belt *5* (shown in Figs. 1 and 2) and which runs from an overhead counter-shaft over idler-pulleys *6*, thence horizontally around a pulley on one of the shafts *y*.

This disposition of the belt 5 permits the lay-beam *d* to move on its carriage while said belt imparts suitable continuous movement to the belt 3.

- 5 As seen in Fig. 2, the two shafts *y* are offset for a distance equal to about half the diameter of the wheels 2, and idler-pulleys 7 are applied to the opposite sides of the belt, as shown in said Fig. 2, whereby while the two sides of 10 the main portion of the belt are parallel there is a space at each end where one side of the belt takes an angular course relative to said parallel courses. The object of this belt construction is for this purpose: When the arm 15 *v* is, by the movements of the rock-shaft *u*, swung into engagement with either one or the other sides of said belt and held in such engagement, the carriage *q* will be slid along the tracks *p* so long as that engagement continues.
- 20 Assuming the parts to be in the position shown in Fig. 2, it would be first swung into engagement with the farther side of said belt 3, (the direction of whose movements is shown by the arrow above the belt,) said arm remaining in such engagement until it arrives at a 25 point opposite the pulley 7 over which that side of the belt runs, and at this point, by reason of the direction taken by the belt, the engagement with said arm *v* will be severed 30 and the movement of the carriage *q* will be arrested. This will leave the arm *v* in the same position relative to the opposite end of the belt that it now occupies in Fig. 2. The 35 means whereby the arm *v* may be operated to be swung alternately into engagement with opposite sides of the belt 3 consist in providing on the frame of the machine suitable abutments against which the crank-shaped ends of the rock-shaft *u* may strike upon the return 40 movement of the lay-beam to the position shown in Fig. 1 after having been moved forward to bear up the work.
- In Fig. 3 the position of the parts is that 45 which they would occupy before the lay-beam has returned to its rearmost position after its beating-up movement, at the completion of which movement the turned-down end of the rock-shaft (shown in dotted lines only) will come into contact with the arm 8, and the arm 50 *v* be thus swung to the opposite side of the belt 3. The carriage *q* will then be moved transversely of the work, as described, the lay-beam going forward to beat up after the conclusion of the shuttle movement, and upon 55 its return the upturned end of the rock-shaft on the side nearest the observer, as shown in Fig. 3, (which will then be inclined toward the rear of the machine,) will come in contact with another arm 9, which is shown only 60 in dotted lines in Fig. 1, which contact will again shift the arm *v* to the opposite side of the belt to effect the return movement of the shuttle. The electromagnet *r* is connected with a suitable source of electricity by wires 65 10, said source being indicated by 12 in the

conventional manner of representing a battery constituting a closed circuit in which the magnets *r* are normally energized. Any other source of electricity of course is equally effective. The wires 10, which run to the magnet, are of course of sufficient length to follow the movements of the carriage *q*.

The warp-threads are indicated by 13 in the drawings and are shown only in Fig. 1. The shuttle is indicated at 14 and is shown in full lines only in Fig. 1 and in dotted lines in Fig. 3. Said shuttle is made flat on the under side thereof and preferably is semi-circular in cross-section and pointed at either end in the usual manner.

Mounted on a suitable standard between the tracks *p* is a shuttle-box 15 at each end of said tracks and adapted to receive the shuttle at the termination of its traverse movement.

The operation of this machine is as follows: The warps having been duly set up in the usual manner and the shuttle provided with weft-threads and placed in one of the boxes 15, the carriage *q* is moved into proper position beneath said box and movement imparted to the belt 3. The arm *v* may then be operated by hand and swung into connection with the proper side of the belt 3 to start the carriage *q* on its traverse motion, the magnets *r* having sufficient power to carry the shuttle 14 across the warp-threads as the magnets move back and forth under the same. After each transverse movement of the carriage *q* preferably the lay-beam *d* is moved forward on its tracks *i* to beat up the weft-thread last drawn across the fabric by means of the usual reeds *h*, the heddles being operated as desired by the cams *f* on the shaft *e* and the beam *d* being operated by the cams *a*, rotary movements being imparted to the shaft *e* by means not shown. The shuttle in its traverse movement might on certain classes of goods draw the weft-thread up too tightly on each selvage edge of the fabric, and to obviate this there is provided on each side of the machine a pivoted finger 16, (suitably supported on the frame, as shown in Fig. 1,) one on each side of the work, in such position that the upturned end 17 of said fingers 110 will lie close to the edge of the fabric and project somewhat above it in such position that when the weft-thread is beaten up the lower end of said finger 16 will be struck by some part attached to the lay-beam *d*, whereby the end 17 will be depressed and the last weft-thread moved over said end against the body of the fabric. Then when the beam retires said end 17 comes up behind said last weft-thread, as shown in Fig. 4, and when the shuttle moves back across the fabric the end 17 of the finger 16 holds the weft-thread against the drag of the shuttle, whereby a uniform selvage edge is formed on the fabric. The end 17 of the finger 16 remains in 115 120 125 130

engagement with the last weft-thread until the beam again goes forward to beat up another. This finger 16, however, and its operating devices do not constitute a part of the 5 present invention, but are to form the subject-matter of a separate application.

While certain specific devices have been described herein as means for shifting the arm *k* from one side to the other of the belt 3, I 10 do not wish it to be understood that I confine myself to these devices as described and shown, for they are but unimportant features of the invention, and other means to effect the shifting of this arm which will have the same 15 function may be used.

The designation of the warp and weft as "threads" is purely conventional. The machine may be used to weave wire-cloth or other fabrics than those composed of fibrous material and generally designated as "threads."

Having thus described my invention, what I claim, and desire to secure by Letters Patent of the United States, is—

1. In a loom in combination with a shuttle, 25 a lay-beam and means for reciprocally moving the latter, a continuous belt whose opposite sides are parallel with the lay-beam and run in close proximity one to another, a sliding carriage near said belt movable in parallelism with the lay-beam, a magnet on said carriage, a device on the carriage for engagement with opposite sides of the belt, and means for shifting said device from one side of the belt to the other to change the direction 35 of movement of the carriage.

2. The combination with the shuttle of a loom of a lay-beam and means for reciprocally moving the same, two vertical shafts supported on said beam, a belt running on said 40 shaft having ribs on the inner surfaces thereof, a carriage and support therefor on the beam, the carriage being slideable in substantial parallelism with the sides of the belt, a shedding device depending from the carriage 45 in proximity to the belt, and means operated by the movement of the machine for effecting

the engagement of said device with opposite sides of said belt alternately, and means on the carriage for moving the shuttle.

3. The combination with the shuttle of a loom, of a lay-beam, a carriage and support therefor on the lay-beam, a belt supported for continuous movement in a plane parallel with the line of movement of said carriage, means for engaging the carriage and belt near each 55 end of the latter, and means of support for said belt whereby each side of the latter may be guided at one end in a direction oblique to the other portion of the side.

4. The combination with the lay-beam of a loom and means for reciprocally moving the same, of a track carried on the beam and parallel therewith, a carriage on said track, an electromagnet on said carriage, and means for energizing said magnet, a device carried on 65 the lay-beam whereby the carriage may have imparted to it reciprocal movement lengthwise of the lay-beam, whereby the shuttle is operated, and means on the carriage operated by the reciprocal movement of the lay-beam 70 whereby the movement of the carriage is controlled.

5. The combination with the lay-beam and means for reciprocally moving the same, of a track on the beam, the carriage movable on 75 the track, an electromagnet on the carriage, and suitable means for energizing said magnet, two vertical shafts supported on the lay-beam beneath the carriage, a belt running on said shaft, the opposite sides of which belt 80 run in proximate parallel lines, a rock-shaft on the carriage, a depending arm on the shaft located between the sides of said belt, ribs on the belt with which said arm may engage, and means operated at the end of the return movement of the lay-beam, whereby said rock-shaft may be oscillated.
